(57) **CLAIM**

I claim the ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of the claimed design of a display screen or portion thereof with graphical user interface.

The sole Figure is being submitted in color.

The outermost broken lines in the Figure illustrate a display screen or portion thereof and form no part of the claimed design. The other broken lines in the Figure illustrates portions of the graphical user interface that form no part of the claimed design.

1 Claim, 1 Drawing Sheet
(1 of 1 Drawing Sheet(s) Filed in Color)

See application file for complete search history.
